UNITED STATES PATENT OFFICE.

HARRY BUXTON HARTMAN, OF SCOTTDALE, PENNSYLVANIA, ASSIGNOR TO ELECTRIC WATER STERILIZER AND OZONE COMPANY, OF SCOTTDALE, PENNSYLVANIA, A CORPORATION OF PENNSYLVANIA.

AIR-COOLED GENERATING UNIT FOR LOW-FREQUENCY APPARATUS.

Application filed October 29, 1924. Serial No. 746,692.

To all whom it may concern:

Be it known that I, HARRY B. HARTMAN, a citizen of the United States, residing at Scottsdale, in the county of Westmoreland and State of Pennsylvania, have invented certain new and useful Improvements in Air-Cooled Generating Units for Low-Frequency Apparatus, of which the following is a specification.

10 This invention relates to ozone generators, and more particularly to an air-cooled generator of the type adapted for use in connection with low frequency currents.

A primary object is to provide a generator of the tubular type which may be economically manufactured, and which will furnish a constant supply of ozone when dry air is supplied to it, thereby particularly adapting the same for use in connection with machines for the purification of water, ventilating apparatus or in the chemical industries.

A further object of the invention is to provide a construction in which the generating portions may be readily washed out with water, without the necessity of dismantling or taking apart thereby effecting a material saving in time in keeping the apparatus in prime operating condition.

30 A still further object of the invention is to provide a tubular generator construction utilizing a glass tube as the dielectric between the generating surfaces, the same having the ends thereof of reduced diameter 35 to provide a graduated air gap between the end of the inner and outer electrode.

With the above and other objects in view which will more readily appear as the nature of the invention is better understood, 40 the same consists in the novel construction, combination and arrangement of parts hereinafter more fully described, illustrated and claimed.

A preferred and practical embodiment of 45 the invention is shown in the accompanying drawings, in which:

Figure 1 is a vertical sectional view of the improved generator.

Figure 2 is a horizontal sectional view 50 taken on the line 2-2 of Figure 1.

Figure 3 is an enlarged detail sectional view of the joint formed between the outer electrode and the end caps.

Similar reference characters designate

corresponding parts through the several figures of the drawings.

As previously indicated, it is one of the objects of the present invention to provide a generator construction which can be economically made, and to that end it is proposed to utilize standardized parts as much as possible, and to also eliminate dielectric elements which are likely to break down under the heat generated by the ozone producing brush discharge between the electrodes.

Accordingly, it is proposed to provide an outer tubular aluminum electrode 1 which is cut from a long section of aluminum tubing and provided at the opposite ends thereof with the flanged rings 2-2. These rings have a tight friction fit with the outside of the tube adjacent the ends, and the flanges 3 thereof are provided with a centering recess 4 to receive the annular shoulder 5 of a recessed end cap designated generally as C. Adjacent the shoulder 5 the said cap is also provided with a flange 6 adapted to abut with the flange 3 so that suitable fastening elements 7 may be utilized to connect the electrode 1 and the cap C together.

As will be observed from the drawings the end caps C are of duplicate construction and therefore a description of one will apply to the other. These caps are preferably of aluminum castings whose recessed portions 8 communicate with the inside of the tubular electrode 1, and whose end walls 9 are provided with a central opening 10 formed to receive suitable packing, and a gland member 11. The opening 10 serves to center the ends of the tubular interior dielectric member D which is preferably made of glass and is of relatively large diameter at its intermediate portion while the ends thereof which pass through the caps are of smaller diameter, thereby providing a relatively restricted annular ozone generating chamber 12 between the body of the glass tube and the electrode 1, and an insulating air gap 13 of progressively increasing width at the ends of the tubular member where the same joins with the caps.

The tubular dielectric member D is provided on its inner face with a surface coating of metal 14, the same extending throughout the portion of large diameter and terminating as indicated at 15 at the

junction of the enlarged body of the dielectric and the ends. It will thus be seen that the interior metallic coating 14 progressively recedes from the electrode 1, to provide an insulating air gap 13 of progressively increasing width, thereby having the effect of tapering off the brush discharge to prevent its concentration and consequent damaging effect on the dielectric, and to prevent the passage of spark discharges.

For the purpose of establishing electrical contact with the interior metal coating 14 which is sprayed on the inside of the tube by any of the well known metal spraying processes now in use, there is provided a novel contact member consisting of the high-tension brass contact post 16 which has fitted thereto a plurality of radially extending glass centering rods 17 while the end thereof carries a pair of divergent spring bronze contact fingers 18 having the rounded contact ends 19 adapted to rest against the metallic coating. In practice the brass contact post 16 is connected to one side of the transformer while the casting is connected with the ground side of the transformer to prevent anyone from being injured. Fig. 1 of the drawing illustrates the manner of connecting the casting with the ground side of the transformer and the high tension contact post with the positive side of the transformer T.

After the device is assembled as indicated in the drawings it is set up in a perpendicular position, so that it may be kept cool by the thermal action of cool air rising within and outside of the generator. If the ozone is taken off at atmospheric pressure, air enters the port 8^a of the lower or bottom cap C and passes upwardly from the recess 8 through the annular chamber 12 in which the brush discharge is formed due to the action of the current jumping from the interior metallic electrode 14 to the outer metallic electrode 1, and as the air rises in the annular chamber it becomes heated and also ozonized, and then passes out as ozone from the port 8^a of the upper casting. The air thus entering at the bottom and being drawn from the top as ozone also serves to cool the generator, while it will of course be apparent that the outside electrode 1 gives off its heat which may freely rise and pull cool air upwardly in its path to keep the outside of the generator sufficiently cool for working purposes. Also due to the fact that the dielectric D and inner electrode 14 are hollow the air will freely pass through the interior of the device and thus maintain the proper temperature conditions in the generator. If the device is used in connection with machines for the purification of water, the ozone may be drawn from the top opening 8^a by an eductor operated by water,

while on the other hand if the device is used for ventilation, or in the chemical industries, a small blower may be connected to the upper port 8^a and air forced downwardly through the annular chamber 12, thereby making it necessary to take the ozone off from the lower opening 8^a.

In addition to the advantages of manufacturing and assembling the present generator, I provide a construction which permits of being readily washed out without being taken apart. That is to say water may be inserted through the bottom opening 8^a and discharged through the top opening 8^a without the necessity of taking the fittings apart. That is of particular importance because when the device is used for generating ozone for air ventilating apparatus the machines are in constant operation, thereby making it impractical to take the generator apart for cleaning and thus lose that much time. By flushing the same with water, the same may be readily and quickly cleaned, and then by temporarily turning on the blower before energizing the tube the water that does not drain out may be quickly evaporated.

From the foregoing it is thought that it will be apparent that the present construction provides a simple, practical and reliable air cooled generating construction, and it will of course be understood that changes in the form, proportion and minor details of construction may be resorted to without departing from the spirit of the invention or scope of the appended claims.

I claim:—

1. A tubular ozone generator including a tubular electrode, end caps fitted thereto and having ports, and a tubular dielectric member carried by said end caps and cooperating with said electrode to provide a relatively constricted ozone generating chamber, a metallic electrode carried by the inside face of the tubular dielectric, and means for establishing electrical connection with the electrode carried within the tubular dielectric member.

2. A tubular ozone generator comprising a tubular electrode and a tubular dielectric assembled therein, a tubular electrode formed by a metal coating adhering to the inner face of the dielectric, and means adapted to be projected within one of the open ends of the tubular dielectric to establish electrical contact with the inside electrode.

3. A tubular ozone generator comprising an outer tubular electrode, recessed end caps detachably fitted to said electrode and having ports, and a combined dielectric and electrode unit insertable within said outer electrode and adapted to be held in said end caps, and means for establishing electrical contact with the electrode portion of said unit.

4. A tubular ozone generator comprising an outer electrode, flanged rings fitted to said electrode, recessed end caps adapted to be secured to said flanged rings, and also having ports, packing glands formed in the end walls of said end caps, a tubular dielectric member having ends of smaller diameter than its medial portion, and said ends being engaged by the said packing glands of the end caps, an inner electrode formed on the inside of the dielectric, a contact consisting of a metallic body and yielding metallic fingers adapted to engage with said inner electrode.
5. An air cooled ozone generator for low frequency currents comprising a tubular outer electrode, a tubular interior dielectric member arranged within said outer electrode and spaced therefrom to provide an ozone generating chamber, a tubular metallic electrode arranged within the tubular dielectric member and adapted to be cooled by the thermal action of air currents passing therethrough, and means for establishing electrical contact with the inner electrode through one of the open ends of the dielectric.
6. A tubular air cooled ozone generator comprising a tubular outer metallic electrode, dielectric supporting means fitted to the ends of said outer electrode, a tubular dielectric engaged by said dielectric supporting means, a metal coating on the inside of the dielectric member and constituting an inner electrode, and means for establishing electrical contact with said inner electrode.
7. A tubular air cooled ozone generator comprising a tubular outer metallic electrode, dielectric supporting means fitted to the ends of said outer electrode, a tubular dielectric having the body and ends thereof of different diameter and engaged by said dielectric supporting means, a metal coating on the inside of the dielectric member and constituting an inner electrode, and means for establishing electrical contact with said inner electrode comprising a contact member having yielding spring fingers adapted to be compressed to enter the small ends of the electrode and afterwards expanded into contact with the metal coating.
8. A tubular air cooled ozone generator comprising a tubular outer electrode, closure means for the end of the electrode, a tubular dielectric member having ends of small diameter fitted in said closure members and its medial portion of larger diameter lying within the tubular outer electrode thereby to provide an ozone generating chamber, a metal coating extending throughout the inside face of the part of the electrode of larger diameter and terminating at the junction of the portions of large and small diameter thereby to provide between the outer electrode and the inner coating an insulating air gap of progressively increasing width, and means for establishing electrical contact with said metallic coating through the open end of the dielectric.

In testimony whereof I hereunto affix my signature.

HARRY BUXTON HARTMAN.
